(57) **CLAIM**

The design for a toy character, as shown and described.

DESCRIPTION

FIG. 1 is a perspective view from above, to the front and to one side of a first embodiment of the new design for a toy character;

FIG. 2 is a front view thereof;

FIG. 3 is a left side view thereof;

FIG. 4 is a rear view thereof;

FIG. 5 is a right side view thereof; and,

FIG. 6 is a top view thereof.

In the drawings, the broken lines depict environmental subject matter only and form no part of the claimed design.
